CUTTING TOOL FOR PIPE CLEANING

Andrew A. O'Leary, St. Paul, Minn.

Application February 21, 1947, Serial No. 730,119

7 Claims. (Cl. 15—104.09)

1

My invention relates to an improvement in cutting tool for pipe cleaning and is particularly designed for use in opening pipes and the like which have become filled with foreign material.

For a number of years it has been rather common practice to open pipes such as drain pipes and the like, which have been filled or partially filled with foreign material, by means of a cutter head mounted on the end of a flexible cable. These cutter heads have usually been welded to the end of a cable so as to be firmly affixed thereto. This structure has been found to involve certain difficulties as the operation of welding the head to the cable seems to effect the metal of the cable in such a way as to cause the head to break off after a number of hours of work. The breaking of the head of the apparatus is serious as it is often necessary to dig out the drain pipe in order to open the same after the head has been lodged in the pipe.

A feature of the present invention resides in the provision of a cutter head which is attached to the end of the cable by means other than welding. As a result the cutter head may be removed from time to time and the cable reversed at intervals, which has been found to lengthen the life of the cable to a considerable extent.

A feature of the present invention resides in the provision of a cutter head mounted upon a hollow cable and having a wire rope extending through the cable. This wire rope in itself is usually not of sufficient strength to be of much use in operating the cutter head. However, the wire rope is considerably more flexible than the outer cable and as a result this wire rope holds together the broken parts of the cable in the event the cable should break. As a result the cutter head may usually be withdrawn from the pipe without difficulty even after the outer cable has been broken.

A further feature of the present invention resides in the provision of a cutter head body in which two or more blades may be removably supported. The cutter head body has an axial aperture therethrough through which the cable may extend. Set screws or similar means are provided for attaching the head body to the cable. The cutter head blades may be freely removed or replaced when the cable is entirely or partially withdrawn from the cutter head body. However, when the cable is in place in the cutter head the blades are held in place thereby.

A further feature of the present invention resides in the particular shape and arrangement of the blades themselves.

These and other objects and novel features of

the invention will become apparent as the following description and drawings will be more fully understood. It is to be understood that the drawings are not drawn to scale, but are for the purpose of illustrating the invention.

Figure 1 is a side elevational view of the cutter head showing the construction thereof.

Figure 2 is a cross sectional view through the cutter head, the position of the section being indicated by the line 2—2 of Figure 1.

Figure 3 is a perspective view of the cutter head body and one end of a blade engaged therein.

Figure 4 is a perspective view of a portion of one of the blades showing the construction thereof.

Figure 5 is a sectional view through the blade illustrated in Figure 4, the position of the section being indicated by the line 5—5 of Figure 4.

The cutting tool is illustrated in the drawings in general by the letter A. This cutting tool is supported on the end of a cable which is indicated in general by the letter B. The cutter head A is mounted on the cable B to rotate in unison therewith.

The cutter head A is constructed as best illustrated in Figures 1, 2, and 3 of the drawings. The cutter head body 10 is rectangular in outline at its largest section, the body including opposed side faces 11 and 12 and opposed top and bottom faces 13 and 14. An aperture extends axially through the body 10. This aperture is partially cylindrical in shape as indicated at 15. The remainder of the aperture through the body 10 is rectangular as indicated at 16. The sides of the rectangular aperture 16 which are parallel to the sides 11 and 12 are substantially flush with the edges of the cylindrical aperture 15. The sides of the aperture 16 which are parallel the top and bottom sides 13 and 14 are spaced apart a distance somewhat greater than the diameter of the aperture 15, thus providing shoulders 17 and 19 between the ends of the cylindrical aperture 15 and the ends of the rectangular aperture 16.

A pair of similar blades 20 are mounted in the body 10 to project therefrom. Each blade 20 is provided with a notch 21 in one side edge thereof near the butt end 22 of the blade. A lug 23 is provided within the head 10 to engage in each of the notches 21. The lugs 23 are integral with the top and bottom inner surfaces 24 and 25 of the rectangular aperture 16 and are spaced from the shoulders 17 and 19. These lugs 23 engage in the notches 21 of the blades 20 and hold the blades from being accidentally disengaged from the head when the tool is in operation.

As will be obvious from an examination of Fig-

ures 1 and 3 of the drawings the blades 20 may be engaged in the head body 10 only when the cable B is not projecting through the apertures 15 and 16. The blades 20 must be engaged in the head with the notches 21 embracing the lugs 23 while the cable is withdrawn from the rectangular aperture 16. Once the blades 20 have been inserted in place the cable B may be inserted through the aperture 16 between the blades 20, the cable then holding the blades from disengagement with the head body.

As best illustrated in Figures 1 and 2 of the drawings the cable B includes an outer helically wound metal wire 26 which is of proper outer diameter to fit within the cylindrical aperture 15 and between the parallel side walls 27 and 28 of the rectangular aperture 16. Furthermore the top and bottom surfaces 24 and 25 of the aperture 16 are spaced apart a distance just sufficient to permit the butt ends of the blades 20 to be interposed between these top and bottom surfaces and the outer surface of the cable 26. As a result the outer surface of the cable engages against the inner opposed surfaces of the blades 20 and holds these blades from movement toward the center of the aperture 16, thereby preventing disengagement of the notches 21 from the lugs 23.

The cable B also includes a wire rope 30 which fits snugly within the cable 26 and is relatively more flexible than the cable 26. This wire rope 30 is usually too light to withstand the rotative strain of the tool when driven, but supplements the cable 26 in its action.

A pair of set screws 31 and 32 extend through the rectangular portion of the body 10 and engage the outer surface of the cable 26 with considerable force, which is preferably sufficient to clamp the cable 26 against the wire rope 30. Thus the end of the cable is firmly connected together by means of the set screws 31 and 32. The head body and the blades may be readily removed from the cable, however, by disengagement of the set screws 31 and 32.

The body 10 preferably tapers from the intermediate rectangular portion toward each end of the body. At one end the body tapers at 33 so as to be circular in cross section at this end. The body also tapers at 34 to be rectangular in outer shape at this end of the body.

In operation the cable B is rotated, acting to rotate the head body 10. This rotation also acts to rotate the blades 20 in unison with the head body. The blades are provided with a cutting edge which engages the obstructing material within the pipe and cuts into the same. The blades 20 are relatively close together at their butt end, but diverge apart by outwardly inclined portions 35 and curve at 36 to converge toward one another at the free ends 37 of the blades. The free ends of the blades are usually tapered as illustrated in Figure 2 of the drawings.

In the event the blades 20 are of too large or too small diameter to fit a predetermined pipe, the head body 10 may be removed from the cable and larger or smaller blades 20 substituted for the improperly sized blades. Also in the event the blades should become locked within the pipe, causing the cable 26 to break, the head of the cutter will always remain connected by the wire rope 30. Thus in the event the outer cable 26 should break, the cable rotating apparatus is stopped without delay and the cable B removed from the pipe by pulling upon the cable. The relative flexibility of the wire rope 30 permits this wire rope to be twisted a considerable amount

after breakage of the outer cable 26 before the wire rope becomes injured.

The tooth construction employed is best illustrated in Figures 4 and 5. In the formation of the teeth the outer surface 39 of each of the blades 20 is beveled at 40 to the inner surface 41 of the blade. Substantially triangular notches 42 are cut in the inner surface 41 of the blades 20 into this beveled edge of the blade. Similar triangular notches 43 are cut in the beveled surface 40 of the blade on the outer side thereof. The notches 42 and 43 are spaced apart the proper distance to produce sharply pointed teeth 44 therebetween. These teeth have a sharp cutting surface therebetween formed by the notches 42 and 43. Thus when the blades are supported in the cutter head body and rotated the sharpened and toothed edges of the blades are brought into contact with obstructing matter within the pipe acting to loosen this matter so as to allow a normal flow of fluid through the pipe.

In preferred form the blades are substantially identical. As a result when supported in the head in the manner illustrated in Figure 1, the edges of the blades are in reversed position so that the cutting edge of both blades will act upon the material in the pipe when the head is rotated in one direction.

In accordance with the patent statutes, I have described the principles of construction and operation of my cutting tool, and while I have endeavored to set forth the best embodiments thereof, I desire to have it understood that these are only illustrative thereof and that obvious changes may be made within the scope of the following claims without departing from the spirit of my invention.

I claim:

1. A cutting tool for use on a cable, the tool including a cutter head having an aperture therethrough, one end of said aperture being substantially cylindrical and the other end of said aperture being substantially rectangular, a pair of blades engageable between said cable and opposed sides of said rectangular aperture portion, co-operable means on said blade and said head holding said blades from longitudinal movement relative to said head when thus engaged, and means for holding said cable between said blades.

2. A cutting tool for use on a flexible cable including a head, an aperture therethrough, one end of said aperture being substantially cylindrical and the other end of said aperture being substantially rectangular, two opposed sides of said rectangular aperture portion being spaced apart a distance substantially equal to the diameter of said cylindrical aperture portion, and the other two sides of said rectangular aperture being spaced a greater distance apart, a pair of blades engageable in said rectangular aperture, and a cable extending into said aperture, said cable having an outer diameter to snugly fit said cylindrical aperture portion, and means for holding said cable in said head, said cable being interposed between the ends of said blades.

3. A cutting tool comprising a head having an aperture therethrough, one end of said aperture being cylindrical and the other end thereof being substantially rectangular, two opposed walls of said rectangular aperture being spaced apart a distance substantially equal to the diameter of said cylindrical aperture portion, and the other two opposed walls of said rectangular aperture portion being spaced apart a greater distance providing shoulder means between each of said re-

maining opposed walls and said cylindrical aperture portion, a cable having an outer diameter to snugly fit said cylindrical aperture portion extending into said aperture, and opposed cutter blades interposed between said cable and each of said other opposed walls of said rectangular aperture portion.

4. A cutting tool comprising a head having an aperture therethrough, one end of said aperture being cylindrical and the other end thereof being substantially rectangular, two opposed walls of said rectangular aperture being spaced apart a distance substantially equal to the diameter of said cylindrical aperture portion, and the other two opposed walls of said rectangular aperture portion being spaced apart a greater distance providing shoulder means between each of said remaining opposed walls and said cylindrical aperture portion, a cable having an outer diameter to snugly fit said cylindrical aperture portion extending into said aperture, and opposed cutter blades interposed between said cable and each of said other opposed walls of said rectangular aperture portion, and cooperable means on said blades and said head to hold said blades engaged with said head.

5. A cutting tool comprising a head having an aperture therethrough, one end of said aperture being cylindrical and the other end thereof being substantially rectangular, two opposed walls of said rectangular aperture being spaced apart a distance substantially equal to the diameter of said cylindrical aperture portion, and the other two opposed walls of said rectangular aperture portion being spaced apart a greater distance providing shoulder means between each of said remaining opposed walls and said cylindrical aperture portion, a cable having an outer diameter to snugly fit said cylindrical aperture portion extending into said aperture, opposed cutter blades interposed between said cable and each of said

other opposed walls of said rectangular aperture portion, notch means in said cutter blades and lug means in said head to hold said blades from outward movement while held in spaced relation by said cable.

6. A cutting tool including a cutting head, a flexible cable secured thereto, a pair of opposed blades secured to said cutting head, each of said blades diverging outwardly from the axis of said cutting head for a substantial distance, and then curved to provide converging end portions, and teeth on said blades, said teeth including pointed portions flush with one surface of each blade, said teeth being formed by spaced notches in both surfaces of said blade.

7. A cutting tool comprising a cutter head, an aperture therethrough, at least a portion of which is rectangular in form, a pair of blades secured to said cutter head, each blade having a notch therein, a lug on said cutter head engaging in said blade to hold said blade from outward movement, and a cable in said aperture between said blades holding said blades engaged with said lugs.
